UNITED STATES PATENT OFFICE.

HENRY ZIEMMERMAN, OF CHICAGO, ILLINOIS, ASSIGNOR TO CHICAGO CARD BOARD COMPANY, OF CHICAGO, ILLINOIS, A CORPORATION OF ILLINOIS.

STEP DISPLAY.

Application filed March 14, 1927. Serial No. 175,247.

This invention relates to a folding card display stand made of a single sheet of material and foldable flatly when it is collapsed but extensible into a step form for display purposes.

The principal object of the invention is, therefore, to provide a folding display stand of this character which is attached at the top and bottom of the display card which forms the steps and has an intermediate portion unconnected to the easel stand so that in folding, certain of the steps will overlap allowing the display card and its easel to fold compactly for shipping and storage. Other objects of the invention will appear hereinafter.

In the accompanying drawing;

Figure 1 is a perspective of a display stand constructed in accordance with the principles of this invention.

Figure 2 is a section illustrating the invention in collapsed form; and

Figure 3 is a plan view in collapsed form.

Heretofore it has not been practical to supply a folding step display device for the reason that if the display member has been attached to an easel it would not fold compactly, and if these two members are not attached, it is very difficult to set them up properly and to keep them in folded position after they are set up. The present invention overcomes these objections by attaching the easel to the bottom and the top of the display member and by so proportioning the steps and the fold lines of the easel stand that both members will collapse into a flat form with certain of the steps overlapping, whereby the folded display not only will occupy a minimum space when it is collapsed, but also it is easily and accurately extended and maintained in its displaying condition.

Referring more particularly to the drawings, a display card or member 1 is provided with opposite scores or cuts 2 and 3, adapting it to fold oppositely upon itself in a more or less zig-zag fashion and to form a plurality of steps 4 with connected risers 5. The uppermost portion of the display member may be a larger portion to form a background for any display carried by the other portion thereof or it may be provided with a score line at the top of its supporting stand which will adapt it to turn backwardly, forming another step.

The easel stand for this display preferably comprises a pair of members 6 and 7 which

may be cut from the same piece of material or may be formed separately, and if connected in pairs, as shown in Figure 1, one of the members is formed with a notched locking tongue 8 adapted to engage in a corresponding locking notch 9 of the other member and to hold the two members spaced apart in upright position.

Each easel member is formed with a front or lower locking wing 10 attached to the inner side of the lowermost step riser 5 and with an upright wing 11 which is attached to the rear of the uppermost portion 12 of the display member 1. The distance between the plane of the riser 12 and the plane of the lowest riser 5 is equally divided by a score line 13 which coincides with the riser line at the rear of one of the steps which form the display so that the width of the distance actually occupied by the steps is equally divided by the score line 13 which therefore requires that the steps included between the wings 10 and 11 be equal in number or else that one of the steps be provided with an additional fold line in order to make the entire structure 75 80 foldable compactly.

At the bottom of each of the easel wings is a score line 15 forming a locking wing 16 for maintaining the easel stand in position, particularly for holding the score line 13 from 85 collapsing when the easel stand is unfolded.

With this construction, it is obvious that the steps, and all of the risers except the lowermost one are unconnected with the easel stand and that they are held in place on the 90 easel stand by their own weight and by the weight of any articles placed thereon. When the steps are even in number, they will collapse in zig-zag fashion with spaced apart sections, as shown in Figure 2, the easel stand 95 members 6 and 7 folding outwardly and collapsing upon themselves, as shown more clearly in Figure 3. It is obvious that any equal number of steps may be combined in a structure as thus described and any odd 100 number of steps may also be provided if an extra fold line, is placed in one of the steps.

I claim:

1. A folding step display stand comprising a display member oppositely-folded to form 105 transverse steps to fold one upon the other in collapsing, and an easel secured thereto at the top and bottom but free intermediate thereof with steps in the edge to support the member in step form and having fold lines coinciding 110

with the risers of one of the steps so that the member and easel fold compactly.

2. A step display stand comprising a continuous member scored transversely to form a succession of connected steps, and an easel permanently secured thereto at top and bottom with an intermediate unconnected portion and having steps in the edge to support the steps of the member when it is extended.
- 10 3. A display stand having a plurality of connected steps, comprising a continuous sheet member scored to fold oppositely, a foldable easel having wings at top and bottom secured to the member and a vertical scoring to fold transversely of the steps, the intermediate portion of the easel being unconnected to the member, the easel and member being foldable upon themselves and foldable together in collapsing.
- 20 4. In a folding display stand, a member and an easel connected to each other only at top and bottom, the member being continuous and scored transversely to form steps which fold together, and the easel having steps to support the steps of the member and being scored to fold at right angles thereto on the line of one of the step risers.
- 30 5. In a display stand of the class described, a member and an easel permanently connected to each other at top and bottom, the intermediate portions being unconnected, the member being continuous but scored to form transverse steps and risers which fold together, and the easel being scored to fold at right angles thereto and supporting each step, one of the folding scores being intermediate the portion covered by the steps.
- 35 6. In a display stand, a continuous display member and an easel connected to each other

at top and bottom with the intermediate portion being unconnected, the member being scored on opposite sides to form an even number of steps which fold together, and the easel being scored to fold at right angles thereto, one of the easel fold lines being midway of the distance between the front and rear edges of the steps when the easel and member are distended so the easel will fold upon itself.

7. A step display stand, comprising a continuous member scored oppositely to form transverse steps, and an easel secured thereto at top and bottom with intermediate steps in the edge to support the steps of the member in distended position, the easel having fold lines transverse to the fold lines of the member and between the front and back of the easel when distended so it will fold upon itself in collapsing, and a scored locking strip at the bottom of the easel to prevent the easel from collapsing when it is in distended form.

8. A step display stand comprising a member scored in opposite sides to form transverse steps, a foldable easel stand comprising a pair of members with wings at top and bottom permanently secured to the top and bottom of the display member, the intermediate portions being unconnected, the easel sections being scored at right angles to the score lines in the member between the front and back thereof when distended adapting the easel sections to fold upon themselves when the display stand collapses, means for locking the easel sections against collapsing, and an additional connecting link between the easel stand sections for locking them apart in spaced relation.

HENRY ZIEMMERMAN.
